ANNEALING BOX

Kenneth J. Deahl, Pittsburgh, Pa., assignor to
 Pittsburgh Annealing Box Company, Pittsburgh, Pa., a corporation of Pennsylvania

Application August 8, 1940, Serial No. 351,847

3 Claims. (Cl. 263—49)

My invention relates to annealing boxes, and while it is hereinafter described as employed in connection with boxes formed of sheet metal, it is to be understood that the invention can be embodied also in annealing boxes of the cast type.

One object of my invention is to provide an annealing box of such form that, for a given weight or gauge of metal, it will have greater strength and resistance to undesirable deformation and, therefore, will be serviceable for a greater number of "heats" than will boxes of other forms.

Another object of my invention is to provide in connection with an annealing box, means for stiffening the lower edge thereof to resist tendency of the side walls of the box to bend or be deformed in a vertical direction through the more rapid heating and consequent earlier expansion of the upper portion of the box when in a furnace.

Still another object of my invention is to provide means for resisting lateral shifting or bowing of the lower edge of the box through uneven rate of heating of the box, and to maintain such lower edge in proper alignment with a sand trough or seal therefor.

A further object of my invention is to provide an annealing box whose lower edge is reinforced against deformation under heat changes, and which, nevertheless, is of such form that it will readily enter the sand which is employed to provide a seal against the entry of furnace gases into the box and loss of gases from the box.

A further object of my invention is to provide a flexible line of juncture between the sides and top of the box, so that the length of the top edges of the side walls may change relative to the bottom edge, without excessively stressing the bottom edges of the box.

A further object of my invention is to decrease the tendency of boxes to "hump" or rise in the center portion, by a combination of a rigid lower edge, a flexible fluting in the side and top walls and the junction thereof and movement-limiting members across the open or bottom edge, the whole functioning in common with the weight of the box to cause expansion strains to be absorbed in the flexible fluting, with low stresses.

In the accompanying drawings, Figure 1 is a perspective view of an annealing box embodying my invention; Fig. 1a is a view showing a blank which is used in forming one of the box ele-

ments; Fig. 2 is a cross-sectional view thereof; Fig. 3 is a fragmentary view taken on the line III—III of Fig. 2, and Fig. 4 is a perspective view of a portion of the under structure of the box, on an enlarged scale.

The box comprises sheet metal plates forming its top and sides that are welded where they abut together at the corners of the box and have oppositely-projecting corrugations or channels 10 and 11 in the walls of the box, the top of the box being also of corrugated channel form whose channels 12 and 13 are aligned at their ends with the channels 10 and 11 respectively, in the side walls. The adjacent ends of the channels 10 and 11 are closed by and connected together by triangular filler members 14 formed of metal plates that are welded to the ends of the channels, the members 14 being provided with end closures 15. Fig. 1a shows a blank of convenient form for use in making these elements.

Plates or strips 16 and 17 that extend lengthwise of the box are welded to the lower ends of the channel portions 10 and 11 with sufficient tightness to prevent any access of furnace gases past these lower edges of the box. Plates or strips 18 are similarly welded to the lower edges 19 at the ends of the box. Stiffening members 13 and 14 are snugly welded to the lower surfaces of the strips 16 and 17 respectively, breathing openings 20, however, being provided in the outer walls of the stiffening members to permit movement of air and thus avoiding excessive pressure within the stiffening members upon heating of the box to annealing temperatures. Longitudinally-extending metal strips 16 are welded in the V-shaped elements 13 and 14 to brace and stiffen the same, the welding preferably being discontinuous at one or more points, in order to permit some movement of air between the space at the lower side of the strips 16 and the space at the upper side thereof. The ends of the members 13 and 14 have plates 17 welded thereto to close such ends and to provide additional strength. The welding of the plates 17 can be sufficiently discontinuous as to provide "breathing" openings for the members 13 and 14. Stiffening members 18 are welded to the under sides of the strip 16 at the ends of the box, and are of the same form as the members 13 and 14. The extremities of the members 18 are shaped to fit against the adjacent sloping sides of the members 13 and 14, and are welded thereto.

The box is shown as mounted upon a furnace hearth or base 20 of any suitable form, and is

provided with the usual sand troughs 21. The hearth 20 is provided with a number of upstanding pillars or bosses 22 which serve to support a base plate 23, upon which sheets 24 or other material to be annealed is placed. This arrangement permits of circulation of the heated air beneath the material being annealed.

A series of tie strips or bars 25 extend cross-wise of the hearth, between the pillars 22, and have their extremities bent to approximately the contour of the stiffening elements 13 and 14, to serve as tie elements that will resist spreading of the sides of the box, and as elements for aligning the edges of the box relative to the sand troughs.

In order to further stiffen the lower edges of the box, and to prevent accumulation of sand upon the upper surfaces of the plates 10 and 11, I weld deflector plates 26 and 27, to the upper sides of the plates 10 and 11, and within the vertically-extending channels of the box body, so that sand which would otherwise accumulate upon the plates 10 and 11, will slide off when the box is lifted from the sand.

It will be seen that not only are the members 13, 14 and 18 of such form that they will readily enter the sand, but that they, together with the plates 10 and 11 and the strips 16, serve to effectively reinforce the lower edge of the box against distortion, notwithstanding the rapid heating of the upper portion of the box relative to the edge thereof which is in the sand seal. This matter of overcoming excessive distortion of an annealing box is important, since the relative rapid heating of the upper portion of the box expands the same, tending to cause the side walls of the box to arch and also causing compressive strains on the lower edge portions of the box, which tends to cause bowing thereof both laterally and vertically. The strains in the sides and top of the box, which tend to cause bowing and permanent distortion, are largely relieved by reason of the continuous channel or flute arrangement that extends up the sides and across the top—each

series of elements 2, 6 and 4 constituting in effect a continuous channel from one bottom edge of the box, across the top and down to the opposite edge. This arrangement provides for flexing under expansion and contraction of the upper part of the box, without permanent deformation—particularly because of the channel arrangement 6 at the corners.

It will be understood that the stiffening channels 13 and 14 may be of other cross-sectional contours than those shown in the drawings, it being desirable, however, to have them taper downwardly in order that they may enter the sand readily. Also, the upper portion of the box may have its flutes of corrugated or triangular form instead of channel form as shown in the drawings.

I claim as my invention:

1. An annealing box open at its lower side, stiffening elements secured to the lower edges of the box and extending longitudinally thereof, and tie bars each having recessed ends for receiving the stiffening elements at opposite sides of the box, the said recesses and stiffening elements being of generally V-form in vertical cross section.

2. An annealing box open at its lower side and having corrugations or the like which terminate at the box edges at said side, stiffening elements secured to and bridging the said extremities of the corrugations, and deflector plates mounted within the corrugations at points above said elements and sloping downwardly toward the lateral edges of said elements.

3. The combination with an annealing box which is open at its lower side, of means for supporting and aligning the lower edges of the box within a sand trough, comprising a tie strip extending crosswise of the box, with its intermediate portion extending to a plane above the lowermost edge of the box and with its ends bent to partially embrace the longitudinal edges of the box.

KENNETH J. DEAHL.
